GARAGE CUPOLA

Julius W. Sonne, Roseville, and Martin O. Bohn, Detroit, Mich.; said Sonne assignor to said Bohn

Filed Aug. 5, 1958, Ser. No. 753,321

1 Claim. (Cl. 98—42)

This invention relates generally to improvements in ventilation structures adapted for use on garages and the like and, more particularly, to ventilator structures of the cupola type.

It is an important object of the present invention to provide a ventilator of the cupola type which may be made generally from four identically shaped roof panels and four identically shaped side panels which are interchangeable with each other and which may be easily and quickly assembled and secured together by means of C channel moulding strips.

It is another object of this invention to provide a cupola type ventilator which may be made from aluminum or any other lightweight metal which can be provided with preferably a baked enamel finish.

It is another object of the present invention to provide a cupola type ventilator embodying a number of basic parts which may be conveniently boxed in a disassembled condition for economy of shipment and which may be readily assembled and installed without the need of any particular skill or the necessity of any particular tools.

It is a further object of the present invention to provide a cupola type ventilator which will afford efficient ventilation of roof openings on the buildings on which the ventilators are installed while at the same time providing good all weather protection over said roof opening.

It is still another object of the present invention to provide a prefabricated ventilator of the cupola type which is adapted to be mounted directly on the roof of a building over a ventilating opening.

It is still a further object of the present invention to provide a cupola type ventilator comprising prefabricated sheet metal roof panels and side panels which are adapted to be rigidly secured together in an assembled structure by means of improved slip joint constructions.

It is a further object of the present invention to provide a cupola type ventilator which is simple and compact in construction, economical of manufacture, efficient in operation, and which may be quickly and easily assembled on the installation site.

Other objects, features and advantages of this invention will be apparent from the following detailed description and appended claims, reference being had to the accompanying drawings forming a part of the specification wherein like reference numerals designate corresponding parts of the several views.

In the drawings:

FIG. 1 is a perspective view of an illustrative cupola type ventilator embodying the principles of the invention;

FIG. 2 is a fragmentary horizontal sectional view of the structure illustrated in FIG. 1, taken along the lines 2—2 thereof and looking in the direction of the arrows;

FIG. 3 is a fragmentary elevational sectional view of the structure illustrated in FIG. 1 and defining a section from the apex of cone 44 down to the lower arrow 3, taken substantially along the line 3—3 thereof and looking in the direction of the arrows;

FIG. 4 is a fragmentary sectional view of the structure illustrated in FIG. 3, taken along the lines 4—4 thereof and looking in the direction of the arrows;

FIG. 5 is a fragmentary horizontal sectional view of the structure illustrated in FIG. 3, taken substantially along the line 5—5 thereof;

FIG. 6 is a fragmentary elevational sectional view of

2

the structure illustrated in FIG. 1, taken substantially along the line 6—6 thereof;

FIG. 7 is a fragmentary elevational sectional view of the structure illustrated in FIG. 1, taken substantially along the line 7—7 thereof;

FIG. 8 is a fragmentary elevational sectional view identical to FIG. 7 but showing the structure mounted on an angled roofing;

FIG. 9 is a fragmentary plan view of the roof corner structure illustrated in FIG. 1, taken substantially along the line 9—9 thereof and looking in the direction of the arrows;

FIG. 10 is a fragmentary elevational sectional view of the structure illustrated in FIG. 9, taken substantially along the line 10—10 thereof and looking in the direction of the arrows; and,

FIG. 11 is a fragmentary elevational sectional view of the structure illustrated in FIG. 10, taken substantially along the line 11—11 thereof and looking in the direction of the arrows.

Referring now to the drawings, and in particular to FIGS. 1, 2 and 9, a preferred embodiment is shown which comprises the four rectangularly shaped side panels 10, 11, 12 and 13, each of which is provided with a plurality of louvers as 14 which are struck outwardly from each of the side panels. As shown in FIGS. 1 and 7, each of the side panels are fixedly secured to the roof of the building on which the ventilator is to be mounted by means of a hold down or retainer angle member, generally indicated by the numeral 15. Each of the angle members 15 includes vertical leg as 16 and a horizontal leg as 17. The horizontal legs 17 are fixedly secured, as by means of screws 18, to the roof 19 on which the ventilator is to be mounted. The retainer angle members 15 are disposed along the insides of the side panels and are fixedly secured thereto by any suitable means, as by the screws 20. Interposed between each of the side panels and their respective retainer angle member 15 is a flexible resilient water proof flashing strip as 21 which is made from rubber or a like material. Each of the flashing strips 21 is provided with a suitable footing 22 which may be bent outwardly to lie under the lower edge of its respective side panel and to engage the face of the roof. The underside of the flashing footing 22 is preferably coated with a suitable adhesive which will provide a water proof sealing engagement with the roof upon which the ventilator is mounted.

FIG. 8 is a fragmentary vertical sectional view similar to FIG. 7 and showing the manner in which the wall structure may be secured to a sloping roof as 23. The similar structural parts as disclosed in FIG. 7 are designated by corresponding reference numerals followed by the small letter "a."

The side wall panels 10, 11, 12 and 13 are connected by means of the following described corner joint structure. As shown in FIGS. 1 and 2, the vertical side edges of each of these side wall panels are folded over outwardly to provide substantially U-shaped folds as indicated by the numeral 24. Each pair of these adjacently disposed folded over corner edges 24 are fixedly secured together by means of a substantially C-shaped channel moulding strip, as generally indicated by the numeral 25. The channels 25 may be easily slipped over a pair of adjacent folded over edges 24 as more fully described herein-after.

As best seen in FIGS. 1, 5 and 9, the roof structure comprises the four triangularly shaped roof panels 26, 27, 28 and 29 which are each provided along the side edges thereof with outwardly folded over corner edges 30 to form a substantially U-shaped corner structure. Each two adjacent folded over edges 30 are fixedly se-

cured together by means of substantially C-shaped channel moulding strips 31. It will be seen that the folded over corner edges of the side panels and roof panels, 24 and 30, respectively, are similarly shaped and are fixedly secured together by the similar C-shaped channels 25 and 31, respectively.

The roof panels are joined to the side panels in the following described manner. As shown in FIG. 6, each of the side panels is bent outwardly and downwardly along the upper edge thereof along a 45° line to the vertical side wall or panel as indicated by the number 32. Each upper edge is then further bent inwardly and then downwardly along its respective panel, as indicated by the numerals 33 and 34 to form an angle shaped portion having a horizontal and vertical leg, respectively. The lower end of the vertical leg 34 is then bent outwardly and upwardly as indicated by the numeral 35 to form a U-shaped joint member. As shown in FIG. 6, the roof panels extend outwardly beyond the upper edge of each of their respective side panels. The lower edge of each roof panel is bent backwardly and inwardly to form an angle shaped portion having the horizontal part 36 and the vertical part or leg 37. The horizontal arm or part 36 is adapted to engage the underside of the portion 33 on its adjacent side panel and the leg 37 is adapted to engage the portion 34 on its adjacent side panel and with the lower edge thereof enclosed by the lip 35.

As shown in FIGS. 10 and 11, the joining edges of the horizontal portions 36 of each of the roof panels are bent upwardly and over to provide the folded over joint parts 38 which are connected together by means of the short pieces of C-shaped channel moulded strips as 39 in a similar fashion as the side and roof panel edges are connected.

The upper edges of the roof panels are bent horizontally inwardly as indicated by the numeral 40, in FIGS. 3 and 5, and meet each other along the joint lines 41. The upper inwardly bent lips 40 are adapted to rest on top of the cross plate 42 and to be fixedly secured thereto by any suitable means, as by the screws 43. The plate 42 and the lips 40 are adapted to be closed to the weather by means of the pyramidal shaped cap generally indicated by the numeral 44. The cap 44 is provided with the rounded corners 45 on the lower edges of the slant faces thereof and with the straight edges 46 around each dehedral angle thereof. The cap 44 is held in place by means of the two cotter pins 47 and 48 and the spring 49. The upper cotter pin 47 extends downwardly through the hole 50 formed in the peak of the cap 44. The cotter pin 47 bears against the washer 51 on the outside of the cap 44 and against the washer 52 on the inside of the cap 44. A waterproof sealing washer 53 made from rubber or the like is interposed between the lower washer 52 and the cap 44 to seal the upper end of the cap against the weather. The lower end of the lower cotter pin 48 bears against the washer 55 which rests on the lower side of the rubber grommet 54 through which the cotter pin 48 passes. The grommet 54 is adapted to be seated in the hole 56 formed in the plate 42. It will be understood, that the cotter pins 47 and 48, and the spring 49 may be replaced by the shaft of a suitable weather vane shaft which may be slipped through the rubber grommet 54 and secured at the bottom end thereof to the roof of the building upon which the ventilator is mounted.

The side panels 10, 11, 12 and 13, and the roof panels 26, 27, 28 and 29, and the C channels 25, 31 and 39, and the cap 44, and the retainer angles 15 are all preferably made from aluminum or a like lightweight weather resistant material.

The ventilator of the present invention is adapted to

be shipped in a disassembled condition and may be easily assembled by the user at the installation point without the need of any special skill or tools. The roof panels would first be assembled and then the cap 44 would be assembled in place. The side panels would then be assembled onto the roof structure one at a time. The side panels may be easily assembled onto their respective roof panels starting the leg portions 37 on the roof eaves into the space between the flanges 35 and the portions 34 and then rotating the side panels counterclockwise, as viewed in FIG. 6. The C channels 25 would then be slipped in place by sliding them upwardly from the bottom edge of the side panels over the flanges 24. The angle members 15 would then be marked out and secured to the roof by means of the screws 18. The ventilator is then mounted over the four angle members 15 and secured in place thereto by means of the screws 20.

While it will be apparent that the preferred embodiment of the invention disclosed is well calculated to fulfill the objects above stated, it will be appreciated that the invention is susceptible to modification, variation and change without departing from the proper scope or fair meaning, of the subjoined claim.

What we claim is:

25 A cupola type ventilator, comprising: a roof structure including a plurality of triangularly shaped roof panels which are each provided along the side edges thereof with outwardly folded over side joint flanges; said roof panels sloping downwardly and outwardly and disposed with each of the side joint flanges of each panel adjacent the side joint flange of another panel to provide a plurality of pairs of adjacently disposed side joint flanges; each of said pairs of adjacently disposed side joint flanges being secured together by a C-shaped channel strip adapted to be slid thereover; each of said roof panels having an inwardly folded horizontal lower edge portion which is provided with a downwardly turned vertical flange; a vertical wall panel connected to the folded lower edge portion of each roof panel; the upper edge of each wall panel being folded outwardly and angularly downwardly to the inwardly folded horizontal lower edge portion of the connecting roof panel, and then extending horizontally inwardly on the same, to the inner end thereof, and then extending vertically downwardly along the inner side of the roof panel vertical flange, and then turned upwardly around the lower end thereof to form a U-shaped joint member having an outwardly spaced lip, whereby, each wall panel may be connected to a roof panel by holding the wall panel in a horizontal position, moving it toward the roof vertical flange and engaging the outer side of said vertical flange with said U-shaped joint member lip, and then swinging the wall panel inwardly to a vertical roof panel connecting position; each of said wall panels having outwardly folded over side joint flanges; each of the wall panels having louvers therein and being secured to an adjacent wall panel by a C-shaped channel strip connecting the wall panel adjacent side joint flanges together; and an angle shaped mounting member secured to the lower end of each of the wall panels.
